[57] CLAIM

The ornamental design for a picture image memory-search apparatus with copying function, substantially as shown and described.

DESCRIPTION

FIG. 1 is a perspective view of a picture image memory-search apparatus with copying function showing my new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a rear elevational view thereof; and

FIG. 7 is a bottom plan view thereof.

FIG. 1

FIG.2

FIG.3

FIG.4

FIG.5

FIG.6

FIG.7

UNITED STATES PATENT AND TRADEMARK OFFICE
CERTIFICATE OF CORRECTION

PATENT NO. : DES. 270,536
DATED : September 13, 1983
INVENTOR(S) : KUNIO HARA

It is certified that error appears in the above-identified patent and that said Letters Patent is hereby corrected as shown below:

IN THE CLAIM:

After "function," insert --or the like,--

Signed and Sealed this
Twentieth Day of December 1983
